SPRAYER

Joseph W. Patterson, Tulsa, Okla., assignor to
 Volume Sprayer Manufacturing Company, Inc.,
 Tulsa, Okla., a corporation of Oklahoma

Application January 21, 1937, Serial No. 121,583

1 Claim. (Cl. 299—89)

This invention relates to new and useful improvements in sprayers.

One object of the invention is to provide a sprayer having an improved receptacle for receiving the insecticide, or other fluid, to be sprayed.

An important object of the invention is to provide an improved fluid receptacle for sprayers which is constructed of two parts suitably connected together, whereby the number of operations necessary in the construction of the receptacle are reduced, which simplifies manufacture and reduces costs.

Another object of the invention is to provide an improved fluid receptacle for sprayers which includes two sections connected together to form a symmetrical body, each section comprising a single piece of material which is pressed, or otherwise formed, into the desired shape; the construction of the receptacle in this manner overcoming the objections to the usual sprayer receptacles which are made of three or more pieces.

A further object of the invention is to provide an improved sprayer fluid receptacle which has a general cylindrical shape in cross-section with its ends rounded, whereby the appearance of the receptacle is enhanced and also whereby its shape prevents tipping of the same, as the rounded ends tend to maintain the receptacle upright at all times.

Still another object of the invention is to provide an improved receptacle of the character described which is so constructed that it may be filled either through the barrel of the sprayer to which it is attached, or through a suitable opening provided in said receptacle.

A particular object of the invention is to provide an improved sprayer receptacle having substantially an ellipsoidal shape, whereby the inner surface of the receptacle is substantially continuous and without angular faces whereby the formation of deposits of extraneous material accumulated or carried by the fluid in such angular faces or corners is eliminated.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an end elevation of a receptacle constructed in accordance with the invention,

Figure 2 is a front elevation of the same,

Figure 3 is a vertical, sectional view taken on the line 3—3 of Figure 2,

Figure 4 is an end elevation of a receptacle showing a portion of a sprayer barrel mounted thereon, wherein the receptacle is filled through the barrel,

Figure 5 is a vertical, sectional view taken on the line 5—5 of Figure 4,

Figure 6 is an end elevation of a receptacle having a portion of a sprayer barrel mounted thereon and having a filler opening provided in said receptacle,

Figure 7 is a vertical sectional view taken on the line 7—7 of Figure 6,

Figure 8 is an end elevation of a receptacle having a neck provided thereon for connecting the receptacle and barrel of a sprayer, and

Figure 9 is a vertical sectional view taken on the line 9—9 of Figure 8.

In the drawings, the numeral 10 designates a receptacle or container which is preferably cylindrical in cross-section and has its ends rounded. This receptacle is formed of two sections, an upper section 11 and a lower section 12, each of which comprises a single piece of material which is pressed, or otherwise formed, into the desired shape. As clearly shown in the drawings, the lower peripheral edge portion of the upper section 11 is offset outwardly to form an external peripheral flange or lip 13 which is adapted to snugly receive the upper peripheral edge portion of the lower section 12 of the receptacle, whereby a lap joint is formed. The two sections are soldered, or otherwise secured, along this lap joint, whereby a most substantial hollow container or receptacle having a single seam is formed of only two pieces of material. The receptacle may be soldered, or otherwise secured, to the barrel 15 of the usual sprayer, as will be hereinafter described.

It is noted that the usual receptacle is formed of a cylinder having its ends closed by end plates or disks. The cylinder is usually formed by bending a flat piece of material into a cylindrical shape and securing, by soldering or otherwise, the transverse edges of the material together, whereby a longitudinal seam extends throughout the length of the cylinder. A pair of end plates or disks, usually flat, are then soldered, crimped or otherwise secured to the ends of the cylinder to close said ends and form the container. Manifestly, three pieces of material, which must be properly cut so as to exactly fit in place, must be employed. Also, machinery must be provided for forming the individual parts and additional

costly machinery is necessary to assemble the parts. This not only involves high manufacturing costs but also increases cost of material due to the number of parts necessary. Further, the 5 finished receptacle has three seams and the tendency of the seams to open or become corroded, resulting in leakage, is great. It is further pointed out that a receptacle formed in such a manner has angular edges or corners which not 10 only detract from its appearance but also increase the possibility of accidental tipping or turning over of said receptacle, causing spilling of the fluid contained therein. Also these corners found in the usual receptacle provide a place for 15 accumulation of gum or other deposits of extraneous material from the fluid in the receptacle which aid corrosion and deterioration of the receptacle. In addition, particles of such deposits frequently flake off and enter the eduction tube 20 to stop up the fluid passage therethrough.

It is noted that this improved receptacle is formed of only two sections, each of which comprises a single piece of material formed as hereinbefore described, and joined along a single 25 seam. It will be seen, therefore, that due to the reduced number of sections required in this receptacle, the number of operations necessary in its formation, as well as the cost of materials and manufacture is materially reduced. The provision 30 of the single seam substantially eliminates leakage due to splitting, corroding or breaking open of seams, because, obviously, the possibility is reduced to one third as compared to the usual receptacle, which has three seams. Further, by 35 forming the receptacle with rounded ends, a symmetrical body is produced, thereby enhancing the appearance of the same. Also, all angular edges and corners are eliminated, and the rounded ends act to maintain the receptacle always in an up- 40 right position because, if the receptacle should accidentally be placed on end, said rounded ends will naturally and immediately return said receptacle to an upright position. Therefore, unintentional spilling of the fluid from the receptacle is substantially eliminated. Obviously, the 45 generally ellipsoidal shape of this receptacle provides a continuous inner surface, and thereby eliminates corners or angular surfaces, whereby normal formation of deposits of extraneous materials from the fluid within the receptacle is 50 eliminated.

Another form of the invention is shown in Figures 8 and 9, wherein the receptacle is formed of two sections shaped in a similar manner to those already described. In this form, however, the edges of both sections are bent outwardly to form laterally directed external flanges which engage each other when the sections are placed together. The flanges are then crimped, or beaded, as at 14, to securely fasten them together, whereby the sections are fastened to each other to form the hollow receptacle.

The receptacle may be mounted on the usual sprayer barrel in any suitable manner and any suitable means for filling the receptacle may be employed. In Figures 4 to 7, the receptacle is provided with an opening 16 which extends transversely thereof, and which is formed in the top of the upper section 11. The forward end of a sprayer barrel 15 is positioned within the open-

ing and is soldered or otherwise secured therein. The opening is of such size as to receive only the lower portion of the barrel, whereby the major portion of said barrel is above the receptacle. The barrel is provided with an opening 17 in its lower portion which is disposed within the receptacle, and the usual fluid eduction tube 18 extends downwardly therethrough into the receptacle. A removable sprayer head 19 is screw threaded on the forward end of the barrel, and it will be seen that this head may be removed and the receptacle filled through the end of the barrel, fluid entering the receptacle through the opening 17 in said barrel.

In Figures 6 and 7 the receptacle is mounted 15 on the barrel in the same manner as hereinbefore described. However, this type of sprayer has an integral head closing the forward end of the barrel. For filling the receptacle, a filler neck 20 is secured in an opening 21 in the upper section 11, 20 and a closure cap 22 is screw threaded on the end of said neck. It will be seen that the receptacle may be filled through this opening and that the cap prevents spilling of the liquid therefrom.

The receptacle is shown mounted on the spray- 25 er barrel in another manner in Figures 8 and 9. In this form a central opening 23 is provided in the top of the upper section 11 and an upwardly extending collar 24 is soldered or otherwise secured therein and has screw threads formed 30 thereon. The sprayer barrel is provided with a cap 25 secured to its underside, which cap is adapted to be screwed onto the collar 24 of the receptacle, whereby said receptacle and barrel are connected together. It will be seen that to 35 fill the receptacle with the fluid to be sprayed, it is only necessary to unscrew the cap by rotating the barrel, and thus the barrel and receptacle are separated and the opening uncovered.

It is noted that the means by which the receptacle is mounted on the barrel and the means by which the receptacle may be filled are not to be limited to the forms shown, as it is conceivable that many variations thereof may be employed without departing from the spirit of the in- 45 vention.

What I claim and desire to secure by Letters Patent, is:

A sprayer comprising a container and an elongate cylindrical pump barrel with a sprayer head at one end and secured adjacent said end to the container, said container comprising an elongate body consisting of two sections united by a seam in a plane extending through its longitudinal axis to form an ellipsoidal receptacle- 55 substantially cylindrical for a distance between substantially hemispherical ends, said elongate container body having an opening in its upper portion and means for connecting the pump barrel therewith so that its sprayer head will 60 extend forwardly beyond the container, said pump barrel having an opening through its lower surface providing communication between pump barrel and container and through which any fluid which may be in the barrel will all drain 65 back into the container, and conduit means extending through said opening in the pump barrel into the container for conducting container fluid to the sprayer head.

JOSEPH W. PATTERSON. 70
